UNITED STATES PATENT OFFICE.

ARTHUR C. EASTWOOD, OF CLEVELAND, OHIO.

LIFTING-MAGNET.

No. 927,513.

Specification of Letters Patent. Patented July 13, 1909.

Application filed June 11, 1906. Serial No. 321,142.

To all whom it may concern:

Be it known that I, ARTHUR C. EASTWOOD, a citizen of the United States, residing at Cleveland, in the county of Cuyahoga and State of Ohio, have invented or discovered new and useful Improvements in Lifting-Magnets, of which the following is a specification.

My invention relates to certain new and useful improvements in the construction of lifting magnets.

The objects of my invention are to produce a lifting magnet, which will have a maximum lifting capacity for a given expenditure of electrical energy; which will be of minimum bulk and weight for a given lifting capacity; and which will be economically produced.

Referring to the drawings, Figure 1 is a side elevation of one form of my invention, 20 and Figs. 2 and 3 are respectively, a vertical central section and a bottom plan thereof. Fig. 4 is a vertical central section of another form of my invention.

In Figs. 1, 2, and 3, the magnetic circuit of the magnet is made up of a single steel casting A, which is circular in plan view as shown in Fig. 3. The casting is annular and encloses in an annular recess the magnetizing coil B. A central hole C passes through the casting A for a purpose to be later described. The lower face D of the outer ring of the framework A forms one pole of the magnet and the lower face E of the inner ring forms a second pole. It will be seen that the magnetizing winding B is surrounded on the top and both sides by the integral casting A. A plate of non-magnetic material F protects the lower face of the winding B. As will be seen in Fig. 3, the plate F is seated against the shoulders D' and E' in the polar faces D and E and is held thereto by screws d and e. Where the magnet is to be used in damp places, the rings of packing may be placed between the plate F and the shoulders 45 against which it seats.

In Fig. 4, a slightly different construction is shown, in which the outer edge of the plate F' is seated in a shoulder in the polar face D as before, while the inner edge of the plate

turns upward in the form of a sleeve embracing the pole piece E and extends upward abutting against the top plate of the magnet. In this case a hole C also passes centrally through the casting A. This serves to place the annular pole E on a relatively larger diameter, thus producing a relatively large pole area with a comparatively small thickness of metal in the pole. Heat from the winding B therefore passes more readily through the thinner wall which is provided and the surface of the cylindrical passage C is available for radiating and dissipating this heat. It will be readily understood from an inspection of the drawings that while the coil B is protected on all sides, it is surrounded by comparatively thin walls and the heat which is generated within may therefore be readily dissipated. By this means it is possible to work the winding at a higher current density, thus producing a greater lifting capacity for a given weight of magnet, at the same time since there are no joints in the magnetic circuit of the magnet proper a given flux may be produced with a smaller expenditure of electrical energy than would be the case if the magnetic circuit were made up of a number of pieces bolted together.

I claim for my invention—

1. In a lifting magnet, a framework of magnetic material constituting the magnetic circuit of the magnet, said framework embracing a top plate, and a pair of spaced poles depending from the top-plate, one pole being surrounded by the other, and a magnetizing coil in the space between the poles, the inner pole having a hollow to dissipate heat and to increase the lifting capacity of the magnet in proportion to its weight.

2. In a lifting magnet, the combination of an annular center pole, an annular concentric outer pole, a magnetic frame or yoke connecting the poles at one end thereof, and an energizing winding, said poles and frame forming a protecting pocket or chamber for the winding.

3. In a lifting magnet, an annular flat magnetic frame, a flange extending from the inner edge of the frame and forming an inner

5 pole, a flange extending from the outer edge of the frame and forming an outer pole, and an energizing winding within the chamber formed between the frame and poles.

4. In a lifting magnet, a tubular inner pole piece, a tubular outer pole piece surrounding the inner pole piece, a yoke or frame connecting the pole pieces at one end, and an energizing winding disposed within the chamber formed by the yoke and the pole pieces.

10 Signed at Cleveland Ohio this 28th day of May, A. D., 1906.

ARTHUR C. EASTWOOD.
